Patrick M. Gilroy & Abner S. Tompkins.
Letters Patent

The schedule referred to in these Letters Patent and making part of the same, containing a description in the words of the said Patrick M. Gilroy & Abner S. Tompkins, themselves, of their improvement in the Damask Loom.

To all to whom these presents shall come: Be it known, that we, Abner S. Tompkins, of North Providence, in the County of Providence, and Patrick M. Gilroy, of Warwick, in the County of Kent, and both in the State of Rhode Island, have invented a new and useful improvement in the damask loom, consisting of the application of water or other power to drive the loom, and the following is a description of the machinery by which this result is produced viz: - Two suitable shafts are placed across near the centre of the loom, running on bearings, one on the lower and the other on the upper girths. The power is applied by a belt to a pulley on one end of the upper shaft - a small gear wheel on the other end of this shaft gears into a large one on the bottom shaft. On the lower shaft is a set of cams the number corresponding with the number of treadles to be used which varies with the kind of work to be performed. The large cam in the above set by means of a large treadle turns the cylinder (as it is commonly called though it is a square block) by which the figure is produced & governs the same. Instead of this treadle, a perpendicular lever with a pulley on it for the large cam to bear on, may be used. The large cam & the large treadle or lever and pulley are connected with the back harness by means of levers, rods & weights to govern them. - The other cams above referred to spring the treadles connected with the front harness, & give the shed for the shuttle to pass through. The shuttle is thrown by a triangle attached to the sword of the lay. Near the ends of the lower shaft are two cams connected with the shuttle motion by a lever rod, the effect of which, is to suspend the motion of the shuttle at pleasure, for any purpose, and leave the loom in operation. The back end of the triangle strikes against the face of a dog, which

is connected with the upper end of the rod aforesaid, and is attached to the plate of the loom on the back side of the sword of the lay -

The lay is suspended on bearings placed on the top plates of the loom, but may be hung at the bottom, as in the common Power Loom. The motion of the lay is produced by sweeps connected with it & a crank on each end of the top shaft. There is a set screw in the above triangle to govern the traverse of the shuttle lever, or the set screws may be put into the sword of the lay. The dog face has a slot in it and is confined to the dog by a set screw - We claim as our improvement the above combination of machinery, constituting the application of power to drive the damask loom, and particularly the large comb & large treadle, or the lever & pulley as a substitute and the two small combs at each end of the cotton shaft.
